UNITED STATES PATENT OFFICE.

ARTHUR C. GAYNOR, OF BRIDGEPORT, CONNECTICUT.

DIE FOR MAKING BULLETS AND SIMILAR ARTICLES.

1,234,654.

Specification of Letters Patent. Patented July 24, 1917.

Application filed June 23, 1916. Serial No. 105,508.

To all whom it may concern:

Be it known that I, ARTHUR C. GAYNOR, a citizen of the United States, residing at Bridgeport, county of Fairfield, State of Connecticut, have invented an Improvement 5 in Dies for Making Bullets and Similar Articles, of which the following is a specification.

This invention relates to the manufacture 10 of bullets and similar articles, and has for its object to provide dies that will stand the stress of continued hard usage much longer than any dies heretofore known to the trade, thereby greatly reducing the cost of production, 15 as dies for making bullets and similar articles are very expensive and the dies heretofore used could not be prevented from getting out of true and the openings therein from partly closing, thus making it impossible 20 to produce bullets within the specified tolerances and necessitating new dies. I have found my present invention especially valuable in the swaging of bullets made from brass, bronze or copper wire, in which blanks 25 shaped wholly differently from the completed bullets are required to be swaged to form.

With this and other objects in view I have devised the novel dies which I will now describe, referring to the accompanying drawing forming a part of this specification, and using reference characters to indicate the several parts:

Figure 1 is a vertical section of my novel 30 dies as in use and the coöperating parts, part of which are in elevation;

Fig. 2 a perspective on a reduced scale, partly broken away, of the upper die block removed and the die separated therefrom, 40 and

Fig. 3 is a similar view of the lower die block and die.

10 denotes the upper die, 11 the upper die block, 12 the lower die, and 13 the lower die block. The lower die block is seated in a recess in a block 14, which rests upon a bed, not shown, and is provided with a circumferential groove 15 which receives the ends of set screws 16 in the block to lock the die 45 block in place. The essential features of the present invention are that both dies taper outward and backward from their faces, the recesses in the die block to receive them being of course correspondingly shaped, and 50 each die is backed up by a removable backing block. Stated in other words, the dies 55

are of smallest diameter at their faces and of greatest diameter at their rear ends and taper uniformly from face to back, and the strains of use are not taken up by the die 60 blocks, but are transmitted to the backing blocks. The recess in the lower die is shaped to form the heel and approximately one-half of the completed bullet. The lower die rests upon a backing block 17 which is received in 65 a corresponding recess in the lower die block and rests upon block 14. 18 denotes an ejector which is seated in recesses in block 14 and the backing block, and the operative portion of which extends through the backing block and into the lower die, the face of the ejector serving in fact as the bottom of the opening in the die.

The back of the upper die bears against a backing block 19 seated in a corresponding recess in the upper die block, which is itself seated in a corresponding recess in the drop 20 and is provided with a circular groove 21 to receive set screws 22 in the drop. The upper die is provided 70 with a longitudinal opening 23, extending through to the back, which receives surplus metal in form of a teat at the point end of the bullet. 24 denotes a guide ring 75 which is rigidly secured to the lower end of the upper die block, as by a drive fit, and is adapted to receive the upper end of the lower die block with a sliding fit. This insures perfect alinement of the die blocks in use, and the backward and outward taper of 80 the dies, which causes the strains of use to be transmitted to the backing blocks, acts to greatly prolong the life of the dies. When it is necessary to change dies, the die blocks are removed, then the dies and backing 85 blocks are pushed out from the front, the new dies are inserted from the back in each die block, the backing blocks are set in place, and the die blocks returned to their operative position and secured there by the set 90 screws. I find in practice that the present construction of dies, die blocks and backing blocks enables the dies to withstand much greater strains for a much longer period of time than has heretofore been possible, 95 largely due to the tapering shape of the dies and a consequent deflection of a relatively large proportion of the excessive strains from a more nearly lateral direction, with consequent effect upon the surrounding die-block, to a more nearly longitudinal direction 100 and ultimately against the backing 105 block.

block. My present dies remain in alinement for a relatively long time, the openings do not commence to close, and the product easily falls within the specified tolerances.

5 Having thus described my invention, I claim:

1. In combination, dies tapering from their bases toward their contiguous faces, die blocks having correspondingly shaped recesses, and backing blocks which support the dies at the bases of the latter and contribute to the reception of the strains of use.

10 2. In combination, dies tapering from their bases toward their contiguous faces, die blocks having correspondingly shaped recesses to receive the dies and other recesses

contiguous to the die recesses, and backing blocks seated in the last mentioned recesses which support the dies through the bases of the latter and contribute to the reception of the strains of use.

15 3. In combination, dies tapering from their bases toward their contiguous faces, die blocks having correspondingly shaped recesses and circumferential grooves, backing blocks which support the dies through the bases of the latter and contribute to the reception of the strains of use, and set screws engaging the grooves in the die block whereby the parts are retained in place.

30 In testimony whereof I affix my signature.

ARTHUR C. GAYNOR.
